(57) **CLAIM**

The ornamental design for a base station for mounting
vehicle accessories as shown and described.

DESCRIPTION

FIG. 1 is a top, front, left side perspective view of a base
station for mounting vehicle accessories showing my new
design;

FIG. 2 is a top, rear, right side perspective view thereof;

FIG. 3 is a bottom, rear, right side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 shown in FIG. 1;
FIG. 11 is an enlarged view of portion 11 shown in FIG. 2;
and,

FIG. 12 is an enlarged view of portion 12 shown in FIG. 8.
The dash-dash broken lines in the drawings depict portions
of the base station for mounting vehicle accessories that
form no part of the claimed design. The dot-dash broken
lines represent boundaries of the enlarged portions and form
no part of the claimed design.
